UNITED STATES PATENT OFFICE.

DAVID E. ROBERTS, OF BUFFALO, NEW YORK, ASSIGNEE TO THE BEAVER COMPANY,
'A CORPORATION OF OHIO.

DRYER FOR PLASTER-BOARD.

1,399,276.

Specification of Letters Patent.

Patented Dec. 6, 1931.

Application filed January 17, 1930. Serial No. 353,122.

To all whom it may concern:

Be it known that I, DAVID E. ROBERTS, a citizen of the United States, residing at Buffalo, in the county of Erie, State of New York, have invented certain new and useful Improvements in Driers for Plaster-Board; and I do hereby declare the following to be a full, clear, and exact description of the invention, such as will enable others skilled in the art to which it appertains to practice and use the same.

This invention relates to drying apparatus and more particularly to apparatus for drying sheet material such, for example, as 15 plaster board, and has for its object the provision of an improved drying apparatus, and in particular an improved apparatus for drying plaster board and the like.

Plaster board consists generally of a 20 sheet or slab of hardened plaster, which may or may not have its surfaces covered with inclosing sheets of paper. It is used extensively in place of lath and plaster as the inner wall of buildings or as the inner 25 wall of a room and is ordinarily nailed or tacked directly to the studding of the building structure. Ordinarily, plaster board is marketed in the form of panels of appropriate dimensions. For example, panels approximately 4 feet in width and approximately 30 8 feet in length are well adapted for ordinary building purposes. In accordance with the usual practice, plaster board is manufactured by a continuous process in which a suitable layer of the plastic material is inclosed between two paper liners and subjected to appropriate pressure, whereupon the board is dried and then cut, 35 into panels of the desired size.

The drying of the plaster board is an important step in the process and must be conducted in such a manner as to properly set or harden the plastic material while preserving without deterioration the sheet 40 form of the article. In accordance with the present invention, the plaster board passes in a continuous manner from the forming or laminating machine into my improved drying apparatus. In this drying apparatus, the board is subjected to appropriate heating influences for driving off the excess of 45 moisture and hardening or setting the plaster. The drier is operated in such a manner that the plaster board passes continuously therethrough and emerges therefrom as a thoroughly hardened and dried board.

The improved drying apparatus of the invention is constructed to receive and dry a plurality of superposed sheets of plaster board. Appropriate conveying means are 50 provided within the drier for carrying the superposed sheets of plaster board therethrough. The drier is heated in the first instance by a closed-circuit heating system having a plurality of superposed heat radiating units or conduits alternately positioned with respect to the conveying means for the superposed sheets of plaster board. In the second instance, the drier is heated by means of a current of an appropriate 55 heating medium which in its exhausted condition carries from the drying apparatus the moisture or steam driven off from the plaster board in the course of the drying treatment.

The novel features of the invention which I believe to be patentable are definitely pointed out in the appended claims. These features, together with the construction and mode of operation of a drier embodying the 60 same, will be understood from the following description taken in conjunction with the accompanying drawing, in which—

Figure 1 is an elevation, partly in section, of the improved drier of the invention;

Fig. 2 is a plan, partly in section, of the drier;

Fig. 3 is a transverse section taken on the section line 3—3 of Fig. 1;

Fig. 4 is a transverse section taken on the section line 4—4 of Fig. 2.

The drier illustrated in the accompanying drawing is arranged to convey therethrough and appropriately dry four superposed sheets of plaster board. To this end, four sets of horizontally disposed rollers 10 are provided as the conveying means for carrying the plaster board through the drier. As viewed in Figs. 1 and 2 of the drawing, the wet end of the drier is at the left and the 95 dry end is at the right. The rollers 10 at the wet end of the drier and in advance thereof are loose so as to allow the wet board to be pushed forward to the drier from the forming or laminating machine without defacing the surface of the wet board. The bottom of the board as it comes from the forming machine and goes through the drier is intended to be the finished or right side thereof. At the dry end of the drier, a 100 suitable length of rollers 10 are provided to allow the board to cool and to permit such 105 110

moisture as remains in the board to evaporate before the panels of board are piled.

The principal heating means of the drier is a closed circuit heating system arranged to carry a current of an appropriate heating medium, such as hot air, through heat radiating pipes or conduits arranged above and below each of the series of rollers for conveying the plaster board through the drier. Thus, it will be observed that within the drier there is provided five series of horizontally arranged radiating pipes or conduits 11. Each horizontal series contains five pipes 11. One series of the pipes 11 is arranged an appropriate distance above the top set of rolls 10 so as to permit the passage beneath this top series of radiating pipes of the top sheet of plaster board. Another series of the radiating pipes 11 is positioned beneath and in proximity to the lower set of rollers 10. The other three series of radiating pipes 11 are disposed between adjacent pairs of the sets of rollers 10, so that the sets of rollers and series of radiating pipes are alternately disposed in substantially horizontal planes.

Each horizontal series of radiating pipes 11 is provided with a manifold 12 communicating with a header 13. The header communicates with each of the manifolds, and the manifolds are arranged to supply the heating medium to their respective radiating pipes.

At their exhaust end, each horizontal series of radiating pipes 11 is provided with a manifold 14. The manifolds 14 communicate at their ends with headers 15 at the side of the drier, and the headers 15 open into a tunnel 16 beneath the drier.

A furnace or burner 17 is provided for heating the circulating medium of the closed circuit heating system. Heat may be generated in the furnace 17 by the combustion of oil, powdered coal, or other suitable combustible material. But ordinarily, oil will be found most suitable for this purpose. The hot gases of combustion from the furnace 17 are drawn into a duct 18 where they commingle with the return or exhaust heating medium from the tunnel 16 and with cold air drawn in in regulable amounts from a cold air chamber 19. A fan 20 serves to provide the desired circulation of the heating medium and forces the medium, heated to the desired temperature, through a duct 21 into the header 13. The cold air chamber 19 is provided with a sliding door to regulate the amount of cold air admitted to reduce the heat to the temperature desired:

A compartment 22 is arranged on each side of the drier. At the hot or wet end of the drier, the compartments 22 communicate with the header 13 and are thereby supplied with the heating medium. The top of the

drier is covered with a tunnel 23 which communicates by means of adjustable dampers 24 with the compartments 22. A fan 25 is provided for withdrawing the exhaust heating medium from the tunnel 23 and discharges the same into a stack 26. It will be noted that the air compartments 22 are supplied from the same source as the radiating pipes 11, but the compartments 22 are not in a closed circuit, but on the contrary, the exhausted heating medium is discharged from these compartments into the stack 26. The compartments 22 are provided for the purpose of assuring uniform heat within the drier and also to carry off the moisture or steam driven off from the plaster board during the drying operation. This moisture or steam passes through the dampers 24 into the tunnel 23, and the dampers are regulated to provide the necessary amount of draft required to carry off the moisture together with the exhausted heating medium.

The frame of the heater may conveniently be made of angle iron and is covered with sheet iron. The radiating pipes 11 are of elongated section and are arranged with their longest axis horizontal, thereby providing the maximum heat radiating surface in horizontal planes. The manifolds at each end of the drier for the radiating pipes are of substantially the same thickness or depth as the pipes themselves, and sufficient space is provided between the adjacent and superposed manifolds to permit the passage of the plaster board conveyed on the rollers 10. As previously stated, the rollers 10 in advance of the wet or hot end of the drier are loose, whereas the other rollers are driven by any suitable means, as, for example, by chains or by a shaft and screw drive. In the accompanying drawings sprocket wheels 30 are secured to one end of the rollers 10 and are adapted to be appropriately engaged by a sprocket chain 31. One of the rollers of each horizontal set thereof is extended through the frame of the heater and forms a drive shaft and may be driven from any appropriate source of power, for example, by means of bevel gears 32.

From the foregoing description, it will be observed that the top and bottom of each sheet of the superposed plaster boards as conveyed through the drier are subjected to the heating influence of the series of radiating pipes 11. Moreover, substantially uniform temperature conditions are maintained within the drier as a result of the provision of the side heating chambers 22. In this manner, the plaster board is thoroughly dried in its passage through the apparatus, and the moisture and steam driven off by the drying treatment is effectively discharged through the stack 26 in the manner hereinbefore described. The plaster board is directly conveyed from the forming or lami-

nating machine to the drier and is not subjected to any treatment or handling which will distort or break the board during the drying operation.

5 I claim:

1. A drier comprising a plurality of superposed conveying means for carrying sheet material therethrough, and a return-circuit heating system having a plurality of 10 closed-circuit heat radiating conduits arranged adjacent the top and bottom of each of said conveying means.

2. A drier comprising a plurality of superposed conveying means for carrying 15 sheet material horizontally therethrough, and a return-circuit heating system having a plurality of closed-circuit heat radiating means alternately disposed with respect to said conveying means, each of said heat 20 radiating means comprising a series of horizontally disposed conduits.

3. A drier comprising a plurality of superposed conveying means for carrying sheet material therethrough, a series of horizontally 25 disposed heat radiating conduits arranged between each adjacent pair of said conveying means, a manifold communicating with the conduits at each end of each of the series of conduits, a header at each end 30 of said conduits communicating with the manifolds thereof, means for supplying a heating medium to one of said headers and for withdrawing said medium from the other header, and means for heating said 35 medium.

4. A drier comprising a plurality of superposed conveying means for carrying sheet material therethrough, a return-circuit heating system having a plurality of heat 40 radiating means alternately disposed with respect to said conveying means, a heating compartment at each side of said drier and adapted to receive a heating medium from said system, and means independent of said 45 system for withdrawing the exhaust heating medium from said compartments.

5. A drier comprising a plurality of superposed conveying means for carrying sheet material horizontally therethrough, a 50 return-circuit heating system having heat radiating means operatively positioned with respect to each of said conveying means, and auxiliary means for supplying heat to said drier arranged to receive heating medium from said system and to independently discharge this heating medium when exhausted.

6. A drier comprising a plurality of superposed conveying means for conveying 55 sheet material horizontally therethrough, a plurality of heat radiating conduits alternately disposed with respect to said conveying means and arranged so that there is a heat radiating conduit adjacent the top and

the bottom of each conveying means, and a 65 return circuit heating system including said conduits arranged to supply a heating medium to the conduits and to withdraw such medium from the conduits and reheat the same whereby the heating medium circulates 70 through said conduits without directly contacting with the sheet material being dried.

7. A drier comprising a plurality of superposed conveying means for conveying sheet material horizontally therethrough, a 75 plurality of heat radiating conduits alternately disposed with respect to said conveying means and arranged so that there is a heat radiating conduit adjacent the top and the bottom of each conveying means, a return circuit heating system including said conduits arranged to supply a heating medium to the conduits and to withdraw such medium from the conduits and reheat the same, auxiliary heating means adjacent the 80 longitudinal sides of the drier, and means for supplying to such auxiliary heating means a heating medium derived from said heating system.

8. A drier comprising a plurality of superposed conveying means for conveying sheet material horizontally therethrough, a plurality of heat radiating conduits alternately disposed with respect to said conveying means and arranged so that there is a heat radiating conduit adjacent the top and the bottom of each conveying means, a return circuit heating system including said conduits arranged to supply a heating medium to the conduits and to withdraw such medium from the conduits and reheat the same, auxiliary heating means adjacent the longitudinal sides of the drier and in communication with the interior of the drier, means for supplying to said auxiliary heating means a heating medium derived from said heating system, and means for withdrawing from the drier moisture driven off from the material being dried in the course of the drying operation and the exhaust 100 heating medium supplied to said auxiliary heating means.

9. A drier comprising a plurality of superposed conveying means for conveying sheet material horizontally therethrough, 115 and a return circuit heating system having a plurality of heat radiating conduits arranged adjacent the top and bottom of each of said conveying means and extending longitudinally in the direction of travel of said 120 means, said conduits being closed throughout the length of said drier whereby the circulating heating medium is maintained out of direct contact with the sheet material being dried.

125 In testimony whereof I affix my signature.

D. E. ROBERTS.
